[57] CLAIM

The ornamental design for a mobile trash bag holder, substantially as shown and described.

DESCRIPTION

FIG. 1 is a frontal perspective view of a mobile trash bag holder embodying our new design.

FIG. 2 is a front elevational view thereof.

FIG. 3 is a side elevational view thereof.

FIG. 4 is a rear elevational view thereof.

FIG. 5 is a top plan view thereof.

FIG. 6 is a bottom plan view thereof.

FIG. 7 is a perspective view thereof in collapsed condition.

The broken lines in the drawing are for illustrative purposes only.

FIG. 1.

FIG. 3.

FIG. 2.

FIG. 4.

FIG. 5.

FIG. 6.

FIG. 7.
